WITNESS:

UNITED STATES PATENT OFFICE.

GEORGE S. CLARK, OF HUNTINGTON, WEST VIRGINIA.

LAMP HOLDER.

Application filed April 3, 1926. Serial No. 99,622

My present invention has reference to an improved means for holding a lamp on a miner's cap.

My object is the provision of a simple, strong and effective clamp which is attached between the visor and the top of the cap, to engage the hook of the miner's lamp in a manner to effectively prevent wabbling or accidental disassociation of the lamp from the cap so that the rays of light from the lamp will be always properly directed at a desired angle in a straight ahead path.

The improvement also consists in other novel features of construction, combination and operative association of elements, a satisfactory embodiment of which is illustrated by the drawings which accompany and which form part of this application.

In the drawings:—

20 Figure 1 is a side elevation illustrating the application of the improvement.

Figure 2 is a front elevation thereof with the lamp removed.

25 Figure 3 is a sectional view approximately on the line 3—3 of Figure 2, showing the lamp in place.

Figure 4 is a rear elevation of the improvement detached from the cap.

30 Figure 5 is a perspective view of the clamp.

Figure 6 is a view similar to Figure 1, illustrating a slight modification.

Figure 7 is a fragmentary elevation of the improvement.

35 Figure 8 is a sectional view substantially similar to Figure 3.

Figure 9 is an elevation looking toward the rear of the improvement.

40 Figure 10 is a perspective view of a modified form of the clamp.

In the drawings C indicates a miner's cap and D the visor thereof. The cap is of the ordinary construction and is designed to have supported thereon, in accordance with

45 this invention, a miner's lamp L. The lamp has its top at its rear provided with the usual hook 8.

Riveted to the front center of the visor D there is the angle end of a fibre strip 1. The 50 strip has its upper end terminating in a line with the top of the cap C, and overlying this end of the strip, and projecting in both directions therefrom there is a second strip 2 of similar material. The strips 1 and 2 have riveted or otherwise secured to the outer faces thereof the rightangular arms

3 and 4 of a metal plate or bracket. The plate 4 has its outer end rounded and extended inwardly, as at 5 to its connection with the plate 3. The rounded end 6 of the 60 angle bracket is centrally notched, as at 7.

Secured by the rivets or analogous means that connect the plate or arm 4 to the strip 3 there is the flat body portion 8 of the metal hook engaging clamp. The body 8 of the 65 clamp has what may be termed its outer edge, formed with a downwardly extending flange 9 which extends from one end of the plate 8 and which terminates a suitable distance from the opposite end of the said 70 plate.

The flange 9, at its last mentioned end is cut to align with the longitudinal plane of the plate 8, and the portion bounded by the cut is rounded to provide the said flange with an inwardly directed 75

spring tongue 10. The plate 8, from points adjacent to the center thereof, is slotted from the inner edge of the said plate, and formed on the ends of the plate, at the said 80

slotted portion thereof there are inwardly directed jaws 11—11. The inner edges of the jaws are contacted by the spring tongue 10 and the spring jaws 11 exert a tension toward each other. The plate 4 of the angle 85

bracket has an opening 12 therethrough, that registers with a similar opening 13 in the strip 2 and these openings, as disclosed by Figure 3 of the drawings, are disposed directly opposite the jaws 11 and the spring 90

tongue 10. It will be apparent that when the hook has its beak passed through the said aligning openings 11 and 12, the same will be frictionally engaged by the jaws 11, and likewise engaged by the tongue 10.

The tongue 10 forces the hook into tight 95 engagement between the jaws and brings the body portion of the hook into the notch 7 in the rounded end of the angle bracket. In this manner it will be seen that the lamp may be easily positioned and firmly retained 100

on the clamp and also that the lamp may be readily removed when occasion requires.

The above description refers particularly to the construction disclosed in Figures 1 to 5 of the drawings, and in the remaining 105

figures I have illustrated a slight modification. The clamp and lamp construction is similar to that disclosed and therefore the parts constituting the same are designated by the same characters which indicate like parts in the foregoing figures. The outer fibre strip 14, which is attached to the visor 110

D, is not, in this instance, contacted by the upper fibre strip 15 which is secured to the top of the cap C. The angle bracket 16, however, is similar to that above described, the horizontal arm of which is riveted to the cap and to the strip 15, while the vertical arm thereof, is riveted or otherwise secured to the strip 14. Arranged centrally between the horizontal arm of the bracket 16 and the strip 15 there is the body plate 17 of the clamp. This body plate is riveted or otherwise effectively secured to the horizontal arm of the angle bracket 16. The plate 17 has on what I will term its outer edge, a downwardly extending flange 18. This flange has one of its ends disposed at a right angle to the longitudinal plane of the flange 18 and forms a spring jaw 19. The body plate 17, at a point opposite the jaw 18, is also formed with a downwardly extending flange 20 that provides the second jaw of the clamp. The jaws 18 and 20 are disposed at inward angles with respect to each other, that is, the said jaws are beveled or inclined from their upper to their lower edges. The strip 15 has its outer edge notched to receive the jaws 19 and 20 therethrough, the flange 18 contacting with the outer edge of the said strip. The hook H of the lamp L has its beak passing through a suitable opening in the horizontal element of the bracket 6 and is received and gripped between the jaws 19 and 20. The angle spring flange 18 is also engaged by the hook which forces the outer portion thereof into the notch 21 in the outwardly extending bead at the connecting portions of the angle elements of the bracket 16.

The simplicity of the construction and the advantages thereof, will it is thought, be perfectly apparent to those skilled in the art to which such invention relates, when the foregoing description is read in connection with the accompanying drawings, it being noted that the spring jaws effectively grip the sides of the hook while the tongue provided by the flanges 9 or 18 exerts a tension upon the hook in a manner to cause the same to be tightly engaged between the jaws and likewise to cant the

lamp L to bring the lower portion thereof into frictional engagement with the strips 1 or 14 as clearly disclosed in Figures 1 to 6 of the drawings.

Having described the invention, I claim:

1. A holder for the hook of a miner's lamp, comprising an angle member fixedly secured to the top and arranged at the front of a miner's cap, and having a notch at the juncture of the walls thereof and the horizontal wall being provided with an opening in which the beak of the hook of the lamp is received prior to the said hook being inserted in the notch, and a spring member fixedly secured to the horizontal branch of the angle member and including angularly disposed downwardly converging resilient inclined jaws, and a back portion which exerts a tension between the jaws for forcing the beak of the hook into frictional contact with the jaws when the said beak is arranged in supported position.

2. In combination with a miner's lamp having a hook thereon, means for holding the lamp to the cap of the miner, comprising a substantially rightangular flat metal plate which is secured to the miner's cap at the front thereof and whose corner is rounded upon itself to provide a bead having a notch centrally thereof, a horizontal flange formed inward of the notch with an opening therein, said notch and opening being so positioned in relation to each other as to adapt them for the reception of the hook of the lamp, a hook engaging clamp fixed to the horizontal flange comprising a rightangular member and formed with downwardly extending resilient spaced separately formed flanges which are inclined downward toward each other, an arched spring portion integrally formed with the rear of the clamp for exerting a tension toward the said flanges and whose lower edge is designed to contact with the beak of the hook, to hold the same in frictional engagement between the downturned portions of the clamp.

In testimony whereof I affix my signature.
GEORGE S. CLARK.
